US00D954953S

(12) **United States Design Patent** (10) **Patent No.:** **US D954,953 S**
(45) **Date of Patent:** **** Jun. 14, 2022**

(54) **IMPLANTABLE ARTIFICIAL BRONCHUS**

(71) Applicant: **Pulmair Medical, Inc.**, San Diego, CA (US)

(72) Inventors: **Marcelo G. Lima**, Del Mar, CA (US); **Murilo Pundek Rocha**, São Paulo (BR); **Herbert Radisch, Jr.**, San Diego, CA (US)

(73) Assignee: **Pulmair Medical, Inc.**, San Diego, CA (US)

(**) Term: **15 Years**

(21) Appl. No.: **29/757,073**

(22) Filed: **Nov. 3, 2020**

(51) LOC (13) Cl. **24-03**

(52) U.S. Cl.

USPC **D24/155**

(58) **Field of Classification Search**

USPC D24/155

CPC A61F 2/07; A61F 2/90; A61F 2/958

See application file for complete search history.

(57) **CLAIM**

The ornamental design for an implantable artificial bronchus, as shown and described.

DESCRIPTION

FIG. 1 is a perspective view of an implantable artificial bronchus showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines illustrate structure or features that form no part of the claimed design.

1 Claim, 4 Drawing Sheets
